O. B. PECK, JR

CENTRIFUGAL CONCENTRATOR

Original Filed March 19, 1924

UNITED STATES PATENT OFFICE.

ORRIN B. PECK, JR., OF LOS ANGELES, CALIFORNIA.

CENTRIFUGAL CONCENTRATOR.

Application filed March 19, 1924, Serial No. 700,433. Renewed November 29, 1924.

To all whom it may concern:

Be it known that I, ORRIN B. PECK, Jr., a citizen of the United States, residing at 1433 West 48th St., in the city of Los Angeles,

5 State of California, have invented certain new and useful Improvements in Centrifugal Concentrators, of which the following is a specification.

10 My invention relates to that type of centrifugal concentrators which operate in successive cycles alternately accumulating a bed or load of concentrates in a rotating vessel, and then discharging the same, and in which an internal rotatable longitudinally 15 movable core member is employed to function with the vessel for accomplishing the purposes of the concentrator, the longitudinal movements of the core in part, being controlled by liquid pressure of a hydraulic 20 cylinder in operating communication with the core member.

In the drawing, Fig. 1 is partly a side elevation and partly a central section of my concentrator, showing the internal member 25 or core moved to its nearest position towards the small or feed end of the concentrating vessel.

Fig. 2, is similar to Fig. 1, but showing the core forced back to the discharge end of 30 the vessel, and having a small part of the apparatus and most of the feed pipe at the feed end broken away.

Fig. 3, is a detached and enlarged longitudinal central section of the hydraulic cylinder and immediately associated members 35 which appear attached to the right hand end of Figs. 1 and 2 in the drawings.

Fig. 4, is a central vertical section of certain relief valve mechanism detached and 40 enlarged, but with its lower portion broken away.

It will be understood, as has been described in my allowed application for Letters Patent, Serial No. 666,277, filed Oct. 45 3rd, 1923, that in this type of concentrator the core member is somewhat shorter in length than the internal length of the concentrating vessel, which permits longitudinal movement of the core within the vessel, 50 and that in operation, at the commencement of the concentrating period of each cycle, the core is in position nearest to the small or feed end of the vessel, also that during concentration it is gradually forced lengthways by operating pressure of the material 55 and liquid fed into the vessel towards the

opposite or large end of the vessel, which movement is suitably and yieldably resisted by liquid pressure in the hydraulic cylinder, as above stated.

It will be further understood that during the unloading or concentrate discharge period of the cycle, the core is automatically forced back by pressure of the liquid in the hydraulic cylinder, to its initial position in the vessel, preparatory to the commencement of another cycle, and my present invention relates more particularly to these phases, with construction and coordination of parts to best effect such results.

In carrying out my present invention I provide a rotatable conical shaped cylinder or concentrating vessel 2, illustrated partly in longitudinal section and partly in side elevation in both Figs. 1 and 2, of the drawings. At the large end of this vessel there is an enlargement 3, in which is formed an internal annular chamber, having comparatively small discharge opening 4, located in a circumferential row which extends from the chamber through the wall of the vessel, for discharge of liquid and material from the vessel.

The vessel at this end is provided with a head 5, which is rigidly and concentrically mounted on and supported by a rotatable hollow shaft 6, which is journalled in boxes 7 and 8 respectively, mounted on the upper end of stands 9 and 10, these stands in turn, being supported on a base plate 11, of the concentrator. The shaft 6 is provided with a pulley 12, by which rotation is imparted to it from any suitable source of power by a belt, not shown, and in this way the concentrating vessel is revolved at the speed which may be desired.

The small end of the vessel is also provided with a head 13, which has a hollow extended centrally located trunnion 14, which is journalled in a box 15, mounted on the upper end of a stand 16, superimposed on the bed plate of the concentrator as are the stands 9 and 10.

Within the concentrating vessel is a core member 17, which is somewhat smaller in diameter and also somewhat shorter than the internal length of the vessel. This core is tapering in form substantially the same as is the internal circumferential wall of the vessel, and is of diameter so when the core is positioned nearest to the small or feed end of the vessel, as illustrated in Fig.

1, there will be a comparatively small annular space or channel 18, around between its exterior and the interior wall or surface of the vessel, which, in operation serves as a concentrating channel or passage.

The core is somewhat in the nature of a large plug, although appearing in the drawings, within the vessel, in longitudinal section. It is intended to be smooth on its circumferential surface, and is securely mounted on the overhanging end of a shaft 19, which is journalled in the hollow of the shaft 6, passing through such hollow and extending into the vessel suitably to support and carry the core therein.

This shaft also extends through and out of the opposite end of the hollow shaft, a desired distance, so as to be journalled at this end, in a box 20, outside of the vessel shaft 6, mounted on the upper part of a stand 21, which is supported on the bed plate of the concentrator as shown.

As means for rotating the shaft 19, and the core, there is a pulley 22, of suitable size mounted on the shaft, which may be driven by a belt, not shown, at any speed desired.

Surrounding the enlargement 3, of the vessel, there is provided a hollow housing or launder 23, with comparatively thin walls, located and held in place on the bed plate of the concentrator as illustrated, and is provided with an annular slot or opening 24, through its wall around adjacent to the enlargement, in radial alignment with the discharge holes 4, in position to receive the discharge of liquid and material from the vessel and permit the same to flow from an opening 26 through the lower part of the launder, to a place of further disposition.

There is a feed pipe 27, best illustrated in Fig. 1, entering the hollow trunnion 14, of the vessel, in a manner to deliver the liquid and material for concentration into the space in the vessel between the small end 45 of the vessel and the small end of the core, in suitable position to flow through the concentrating channel 18, to the large end of the vessel, and to discharge through the holes 4, for that purpose.

The feed pipe is intended to be connected with any suitable source of supply for feed of liquid with material to be concentrated, and its flow to the vessel is controlled as desired by a valve 28, located in such pipe. This pipe is provided with a pipe 29, for supply of clean water at such time as clean water is desired in operation, and there is also a valve 30, located in this branch, by which the flow of water to the vessel may be controlled and regulated as and when desired.

Preferably in extended axial alignment with the shaft 19, or substantially so, there is a hydraulic cylinder 31, securely but removably connected to the journal stand 21,

as illustrated in the drawings, in which a suitable piston head 32 is located, having an attached member 33, extending in direction of the outer end of the core shaft 19, to which this member is differentially connected through elements embodying preferably a roller bearing 34, positioned within the chamber formed by the member 33. The member 33 also has a ring plate 33' attached to it, as best shown in Fig. 3, which assists in effecting engagement with the shaft and also serves as a guide for the member 33.

The member 33 and its associated parts, as has been explained, serve to rotatably engage the piston head and the end of the core shaft, in this way transmitting liquid pressure from the cylinder so as to render such pressure effective as desired in resisting longitudinal movement of the core towards the discharge end of the vessel during concentration, also as the agency by which the core is automatically forced towards the feed end of the vessel during discharge of concentrates. The outer end of the hydraulic cylinder is closed by a head 36, and there is a hydraulic pipe 37, suitably connected to the cylinder to supply liquid in the space between this head 36 and the piston head 32, for developing pressure for the purposes herein explained.

Liquid supplied to the hydraulic cylinder through the pipe 37, is preferably from a yieldable or elastic source, as from an accumulator drum or receiver 38, as illustrated in the drawing, the upper part of the drum serving as an air chamber, which is supplied with air to afford elasticity to movement of the liquid. The liquid is forced into the accumulator drum under desired pressure by suitable means, as by a force pump, not shown, connecting with a pipe 39.

The pipe 37 connecting with the hydraulic cylinder is provided with an adjustable relief valve or means 40, which is shown in section in enlarged detail in Fig. 4, so that the pressure exerted in the hydraulic cylinder may be regulated and adjusted to serve the conditions of operation of the concentrator as desired. In the drawings the accumulator or drum is illustrated as partly in section and partly in elevation, with liquid in the lower portion, while the space in the upper part serves as an air space.

In operation, during the concentrating period, the vessel is rotated at a desired comparatively high rate of speed, and the core member is rotated at a desired differential speed to that of the vessel, these speeds being adjusted separately and relatively to effect the concentration wanted.

Under these conditions a suitable volume of material mixed with the water for treatment is fed to the vessel through the feed pipe 27, into the space between the small end of the vessel and that end of the core,

thence flowing into the concentrating channels where the heavier portions to be separated and recovered, accumulate in said channel in a progressive accretion or bed, 5 18' as illustrated in Fig. 2, while the lighter or waste portions are hydraulically scoured by the liquid passing through the concentrating channel as a result of operation, and are washed or carried on through such chan-

nel to discharge from the vessel through the openings 4, and into the launder, passing on out through the opening 26, in the lower part of the launder for further desired disposition.

15 During this time of concentration, the vessel operating at a comparatively high speed, the liquid and material which accumulates in the feed end of the vessel, as the same are being fed therein, are subjected to highly developed centrifugal force, resulting in a hydraulic pressure, strongly tending to force the core endways from the feed end of the vessel towards the large end. This pressure is much augmented as the concentrates bed in the concentrating channel, from the fact that such bedding gradually fills in the concentrating passage and decreases the size of the flow channel for the liquid and material from the feed end. This 25 endways pressure on the core, as above explained, is transmitted through the shaft 19, and its associated part, to the liquid in the hydraulic cylinder, so such liquid forms a resisting energy to the pressure on the 30 end of the core to force the latter towards the large end of the cylinder.

The liquid pressure in the hydraulic cylinder is adjusted through the regulating or relief valve 40, so as to balance with the 40 pressure of liquid accumulated in the small end of the vessel, in a manner to yield to the latter pressure as desired, permitting the core to be gradually forced back towards the large end of the vessel, resulting in 45 maintaining the flow passage for material in the concentrating channel of suitable and desired size, while accretion of concentrates therein progresses. This continues until the core has been forced to its extreme position 50 at the large end of the vessel, which has enlarged the channel to its maximum size, permitting the same to have become largely filled with bedded concentrates.

When the core has been fully moved to 55 the large end of the vessel, the feed of material for concentration is closed off by the valve 28; the speed of the concentrating vessel very much reduced and clean liquid introduced through the branch pipe 29, resulting, during the low speed of the vessel, in a relatively low centrifugal force and relative low pressure of liquid in the feed end of the vessel, thereby changing the balance of pressure between this point and the liquid 60 in the hydraulic cylinder, so that the pres-

sure in the hydraulic cylinder will be relatively largely in excess, which condition will force the core again to the small or feed end of the vessel, while the bedded concentrates are washed out under the low condition of centrifugal force, restoring the initial relative positions of the core and the vessel for commencement of another cycle of operation.

70 The concentrates are flowed from the vessel, while being discharged, through the same openings 4, as was the waste during the concentrating period of the cycle, but may be diverted by any suitable means to a desired place, as they flow from the opening 75 in the lower part of the launder.

The concentrates having been discharged from the vessel, the latter is accelerated to its suitable high speed for concentration; the feed of clean water discontinued; the 80 feed of material for concentration restored, and the operation may be repeated, thus progressing in successive cycles.

85 In Fig. 4, is illustrated an enlarged detail of the relief valve 40, to more clearly show 90 its parts, in which it will be seen there is a plunger 41, suitably fitted in the barrel portion of the valve, adapted to be moved in one direction by liquid pressure in the lower part of the valve, and to be forced 95 downward against such pressure by a spring 42, pressing against the same. This spring seats at its opposite end against a member 43, which in turn rests against the end of an adjustable screw 44, so that the member 43, 100 may be forced down or permitted to rise, thereby regulating the tension of the spring and the pressure which the same exerts on the plunger to resist the liquid pressure in the lower end of the valve.

105 Through the side of the valve barrel, above the plunger closure seating, is an opening 45, shown in Fig. 4, for escape of liquid when the pressure is sufficiently great under the plunger to force the plunger up to that extent, thereby affording relief to the liquid in the valve, and within the cylinder 31, in such manner regulating or balancing the pressure of such liquid with the tension of the adjustable spring of the valve.

110 It will be seen that in this way, from the fact that the valve is connected either directly or through medium of suitable pipes with the hydraulic cylinder, the pressure in such cylinder may be regulated as desired 115 to meet the requirements of operation, suitably balancing it with the pressure in the vessel and maintaining a constant desired size of the concentrating passage to effect desired concentration.

120 It will further be understood that this valve serves in a large measure to maintain a desired elasticity to the liquid supply in the drum 38, or accumulator, for the hydraulic cylinder.

What I regard as new and desire to secure by Letters Patent is:

1. In a centrifugal concentrator adapted to operate in successive cycles, each embodying a period of separation and accumulation of a bed of concentrates, and a period of discharging said concentrates, the combination of a rotatable tapering concentrating vessel, a relatively differentially rotatable core within said vessel adapted to be forced endways during operation in part by liquid pressure within the feed end of the vessel, means for supporting and rotating said core, and yieldable means in axial extension with said core for resisting longitudinal movement of the core in direction from the feed end of the vessel, substantially as described. 70
2. In a centrifugal concentrator adapted to operate in successive cycles, each embodying a period of separation and accumulation of a bed of concentrates, and a period of discharging said concentrates, the combination of a rotatable tapering concentrating vessel, a relatively differentially rotatable core within said vessel adapted to be forced endways during operation in part by liquid pressure within the feed end of the vessel, means for supporting and rotating said core, and yieldable means in axial extension with said core adapted to resist longitudinal movement of the core during concentration, in direction from the feed end of the vessel and to automatically force said core towards the feed end of the vessel during the concentrate discharge period, substantially as described. 75
3. In a centrifugal concentrator the combination of a rotatable concentrating vessel, a rotatable core within the vessel, provided with means for supporting and rotating the same, said core adapted to be forced endways within the vessel during concentration in part by liquid pressure at the feed end of the vessel and yieldable means embodying a hydraulic cylinder for resisting said endways movement of the core in extended axial alignment to said core, substantially as described. 80
4. In a centrifugal concentrator the combination of the rotatable concentrating vessel, a rotatable core within the vessel, adapted to be forced longitudinally in direction from the feed end of the vessel by liquid pressure in said vessel, means for supporting and rotating said core, means for resisting said endways movement of the core during concentration, and for forcing said core towards the feed end of the vessel during the concentrate discharge period, embodying a hydraulic cylinder in axial extension with core, substantially as described. 85
5. In a centrifugal concentrator the combination of a rotatable concentrating vessel, a rotatable core within the vessel provided
- with means for supporting and rotating the same, said core adapted to be forced endways within the vessel during concentration in part by liquid pressure at the feed end of the vessel, and adjustable yieldable means embodying a hydraulic cylinder for resisting the endways movement of said core from the feed end of the vessel, communicating with a liquid container affording a yieldable liquid supply to said cylinder, substantially as described. 90
6. In a centrifugal concentrator the combination of a rotatable concentrating vessel, a rotatable core within the vessel provided with means for supporting and rotating the same, said core adapted to be forced endways within the vessel during concentration in part by liquid pressure at the feed end of the vessel, yieldable means embodying a hydraulic cylinder for resisting endways movement of the core communicating with a liquid supply container provided with an air pressure chamber to afford elasticity to said liquid supply, substantially as described. 95
7. In a centrifugal concentrator, the combination of a rotatable concentrating vessel, a rotatable core within said vessel, adapted to be forced longitudinally during concentration in part by liquid pressure in the feed end of the vessel, a shaft supporting and rotating said core, journaled outside of said vessel, means extended in axial alignment with said shaft and differentially engaging the end thereof, for resisting the endways movement of the core, substantially as described. 100
8. In a centrifugal concentrator, the combination of a rotatable concentrating vessel, a rotatable core within said vessel, adapted to be forced longitudinally during concentration, in part by liquid pressure in the feed end of the vessel, a shaft for supporting and rotating said core, journaled outside of the vessel, means in axial alignment with said shaft and differentially engaging the end thereof, for resisting the endways movement of the core, embodying a hydraulic cylinder, communicating with means adapted to yieldably supply liquid pressure to said cylinder, and means for regulating the intensity of said pressure, substantially as described. 105
9. In a centrifugal concentrator, the combination of a rotatable concentrating vessel, a rotatable core within said vessel adapted to be forced longitudinally during concentration, in part by liquid pressure in the feed end of the vessel, a shaft for supporting and rotating said core, journaled outside of the vessel, means embodying a hydraulic cylinder removably supported in extended axial position to said shaft, provided with a piston head cooperating with members in rotatable engagement with the 110
- 120
- 125
- 130

end of the shaft and adapted through instrumentality of liquid pressure in the cylinder to yieldably resist endways movement of the core, and means for supplying liquid pressure to the cylinder, substantially as described.

10. In a centrifugal concentrator, the combination of a rotatable concentrating vessel, a rotatable core within said vessel adapted to be forced longitudinally during concentration, in part by liquid pressure in the feed end of the vessel, a shaft for supporting and rotating said core, journalled outside of the vessel, means embodying a 15 hydraulic cylinder removably supported in

extended axial position to said shaft, provided with a piston head cooperating with members having a roller-bearing in rotatable engagement with the end of the shaft and adapted through instrumentality of liquid pressure in the cylinder to yieldably resist endways movement of the core in direction from the feed end of the vessel, and to automatically force said core to the feed end of the vessel during discharge of concentrates, and means for supplying liquid under pressure to the hydraulic cylinder, substantially as described. 20 25
